IGNITION LOCK AND SWITCH

Rufus J. Beagles, Fort Pierce, Fla.

Application July 5, 1944, Serial No. 543,588

3 Claims.

(Cl. 200—42)

This invention relates to a combined lock and switch for the ignition circuits of motor vehicles, etc., one of the objects being to provide a structure of this character from which the ignition switch can not be opened until the key has been removed from the lock.

It is a well known fact that drivers frequently leave their keys in the ignition lock and if they thereafter close and lock the vehicle doors accidentally, the problem of getting into the car becomes a difficult one and frequently necessitates breaking a glass. Theft is also invited by leaving the key in the lock.

The present invention has for its object the provision of a novel form of switch and lock which requires removal of the key in order to stop the motor.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawing the preferred form of the invention has been shown.

In said drawing:

Figure 1 is a longitudinal section through the lock and showing the normal positions of the parts when the key is removed.

Figure 2 is a similar view showing the relative positions of the parts when a proper key is inserted.

Figure 3 is another view like Figs. 1 and 2 showing the ignition circuit closed and locked when the key is turned following its insertion.

Referring to the figures by characters of reference, 1 designates the housing of the lock which contains the usual lock mechanism comprising spring-pressed pins 2 adapted to match with pins 3 located in a rotatable key-receiving barrel 4. Under normal conditions a key of the proper size and configuration, when inserted into the barrel, will allow the pins to adjust themselves so that their meeting ends will be flush with the surface of the barrel, thereby allowing the barrel to be rotated to open or close the ignition switch. It has frequently happened, however, that the key has been left in the lock after the current has been turned off, with the disadvantages resulting as heretofore explained.

In the present structure the inner end of the barrel is provided with a cam 5 with which co-

operates a second cam member 6 joined by a stem 7 to a bar 8 extended longitudinally within the housing. This bar is slidably mounted, the inner end being in position in a guide socket 9 while adjacent to its other end there is located a web 10 having an opening 11 in which the bar is mounted to slide. A chamber 12 is provided in the housing between the web 10 and the adjacent end of the housing and one end of the bar is extended into this chamber. The bar is formed of resilient material and that portion thereof located in chamber 12 has an opening 13 extended therethrough.

A pin 14 corresponding with the pins 2 is located in the housing and is mounted to slide within an opening 15 extended at right angles to the chamber 12. This pin is adapted to be contacted by a pin 16 corresponding with pins 3 and when a key of proper design is used, the pin 16 will contact with pin 14 at the margin of the barrel 4 when the other pins 3 and 2 are similarly positioned.

All of the pins 2 and 4 are provided with springs 17 for exerting a constant pressure against them. The spring engaging pin 14, however, is extended around a stem 18 projecting from pin 14 and into chamber 12 where it normally presses against the flat inner side of the resilient strip 18 at a point between the opening 13 and the free end of the strip. This strip is maintained in this position relative to the stem 18 by a coiled spring 19 mounted thereon and bearing at one end against web 10 while its other end bears against the stem 7. This stem 35 serves to hold the driven cam member 6 normally pressed against the driving cam member 5.

A contact is carried by the driven cam member 6 and its stem 7 as indicated at 20 and another contact 21 is located adjacent thereto but normally spaced therefrom. These two contacts are included in the ignition circuit and when they are spaced apart the circuit is broken.

When the key K is removed from the lock the pins are in their normal positions with their meeting ends out of alignment with the surface of the barrel and with the free end portion of the strip 8 resting on the end of the stem 18. When the key is inserted, the several pins are shifted into position to release the barrel for rotation and when pin 16 thrusts against the pin 14, it causes the stem 18 to flex the projecting end of strip 8 upwardly. The key is then turned and this action causes the barrel to turn with it. The rotation of the barrel and consequent rotation of the driving cam 5 will result in the driven cam 6

being forced toward the pins 2 with the result that contact 20 will be brought against contact 21, thereby closing the ignition circuit, and the opening 13 in the end portion of strip 8, will be brought over the stem 18. Consequently the flexed strip will snap downwardly so that the stem 18 will enter opening 13, thereby locking the strip 8 against return movement under the action of its spring 19 which was placed under compression when the contact 20 was forced against contact 21. The ignition circuit is now closed and the switch is locked in closed position by the cooperating parts 8 and 18. As long as the key remains in the lock after the lock has been turned to produce the result described, the ignition circuit will remain closed. However should it be desired to stop the engine by breaking the ignition circuit, it is first necessary to rotate the key and the barrel in the reverse direction. This will cause the driving cam 5 to move away from the driven cam 6 but the circuit will remain closed until the key is removed from the lock. At that time the spring bearing against the pin 14 will thrust said pin downwardly with sufficient force to cause the stem 18 to withdraw from opening 13. Consequently the cam 6 will be thrust back against cam 5 by the expanding spring 19 and the opening 13 will be moved out of alignment with the stem 18. Thus the circuit is broken.

When the key is again inserted, the cooperating pins 16 and 14 will again push stem 18 upwardly against the projecting end of strip 8 so as to flex it after which, by rotating the key, the cams will again be actuated to close the circuit and to cause the moved strip 8 to be engaged and locked by stem 18 entering the opening 13.

Importance is attached to the simplicity of this device and to the further fact that it can be used wherever it is desired to have a key-controlled switch which can be open only by the removal of the key.

What is claimed is:

1. The combination with a key-operated barrel lock including cooperating pins, of a cam rotatable with the barrel of the lock, a structure shiftable by the cam when rotated in one direction, said structure including the movable contact, of a switch and a flexible strip having an opening, means movable with one of the pins for movement

into the aperture when said strip is shifted in one direction by the cam and the switch closed, means for automatically disengaging the pin from said strip when the key is removed, and means for automatically returning the strip and the movable contact to their initial positions when the strip is released, thereby to open the switch.

2. In a device of the class described the combination with a housing including a key-receiving barrel rotatably mounted, fixed and movable switch contacts, and an elongated strip movable with the movable contact and having an opening, of cooperating pins in the housing and barrel proportioned to release the barrel for rotation when a key of proper contour is inserted, yielding means for holding the contacts normally spaced apart, means on one of the pins for holding the strip under pressure when a key is in position, means operated by the rotation of the barrel for shifting the movable contact against the other contact to close the switch and for shifting the strip out of normal position, there being an aperture in the strip, means on one of the pins for entering the aperture when the strip is shifted, and means for releasing the strip and the movable contact when the key is withdrawn.

3. A switch and lock for ignition circuits or the like including a housing, a rotatable key-receiving barrel therein, pins in the housing and barrel respectively cooperating to release the barrel for rotation when a proper key is inserted into the barrel, a stem on one of the pins, a resilient locking strip slidably mounted in the housing and having an opening, said strip being positioned to flex under pressure from said stem when its pin is shifted by the insertion of a key, a switch including a contact movable with the strip and a stationary contact, means actuated by the rotation of the barrel for closing the switch and shifting the flexed strip to position the opening to receive the stem thereby to lock the strip against movement and the switch closed, means for actuating the stem and its pin to withdraw said stem from the opening when the key is removed, and means for returning the strip to its initial position and opening the switch when the barrel is rotated to its initial position and the key removed.
